CLAIM

The ornamental design for a grille structure, as shown and described.

DESCRIPTION

FIG. 1 is a top, front, right side perspective view of a first embodiment of a grille structure showing our new design; FIG. 2 is a front elevation view thereof; the rear elevation view being identical;

FIG. 3 is a right side elevation view thereof; the left side elevation view being identical;

FIG. 4 is a top plan view thereof;

FIG. 5 is a top, front, right side perspective view of a second embodiment of a grille structure showing our new design; FIG. 6 is a top plan view of a third embodiment of a grille structure showing our new design; and,

FIG. 7 is a top plan view of a fourth embodiment of a grille structure showing our new design.

In the drawings, the broken lines in FIGS. depict portions of the article that form no part of the claim.
